RECTIFIER SYSTEM.

1,214,116.

Specification of Letters Patent. Patented Jan. 30, 1917.

Application filed April 1, 1915. Serial No. 18,508.

To all whom it may concern:

Be it known that I, ALFRED L. ATHERTON, a citizen of the United States, and a resident of Wilkinsburg, in the county of Allegheny and State of Pennsylvania, have invented a new and useful Improvement in Rectifier Systems, of which the following is a specification.

My invention relates to current rectifying systems, particularly those embodying rectifiers of the vapor-arc type, and it has for its object to provide means whereby systems of the character indicated may be started in operation in a simple, economical and effective manner.

The single figure of the accompanying drawing is a diagrammatic view of a rectifier of the vapor-arc type, together with suitable supply, load and starting circuits constructed in accordance with my invention.

In an application for Letters Patent of Q. A. Brackett, Serial No. 23,427, filed concurrently herewith and assigned to the Westinghouse Electric & Manufacturing Company, is disclosed a system of starting vapor rectifiers by an electromotive force induced in an auxiliary winding on the transformer, said auxiliary winding being idle except during the starting period.

By my invention, I provide connections whereby the auxiliary inducing winding is normally employed as a maintaining reactance device for the vapor rectifier and is adapted for the generation of a starting electromotive force by an alteration in the magnetic conditions within the transformer core.

Referring to the accompanying drawing, a rectifier of the vapor-arc type is provided with suitable anodes 2-2, a cathode 3 and an auxiliary starting anode 4. Current is supplied to the main anodes 2-2 from the terminals 5-5 of the secondary winding of an auto-transformer 6, the primary winding of which is energized from suitable mains 17.

The primary and secondary windings of the transformer 6 are each split in halves and one half of each is mounted upon each side of a rectangular core 15 of the usual type. The core 15 is provided with a middle leg 7 in inductive relation to an auxiliary winding 8, one terminal of which is

connected to the cathode 3 and the other, through a suitable battery load 9, to the mid point 10 of the secondary winding of the auto transformer 6. The lower terminal of the winding 8 is also connected, through a regulating resistance member 11 and a switch 12 to the auxiliary starting anode 4.

An auxiliary load, comprising a resistance member 13, may be connected across one half of the primary winding of the transformer 6 by a suitable switch 14.

Under normal operating conditions, the two halves of the primary winding serve as sources of magnetomotive force for producing flux in the core 15 and, considering the magnetic potentials throughout said core in a given direction, the instantaneous values are such that there is a rise in magnetic potential as one traverses, for example, the portion of the core embraced by the right hand primary winding; there is a fall of magnetic potential in traversing the lower cross member; there is another rise in magnetic potential in traversing the portion of the core member embraced by the left hand primary winding and a fall in magnetic potential in traversing the remainder of the core. All this action is in strict analogy to the rise and fall of electric potential in a closed electric circuit containing a plurality of sources and a plurality of resistance members interspersed therebetween and, furthermore, by the application of Kirchoff's Second Law, the sum of the increments and decrements in magnetic potential through the core 15, due to the magnetizing action of the primary windings, is equal to zero. The middle member 7 of the transformer 6 is symmetrically disposed with respect to the two halves of the primary winding and, accordingly, the two ends thereof are at equal magnetic potential with respect to the primary or working flux and no magnetic flux flows therethrough to induce an E. M. F. in the winding 8 when the secondary winding is open.

Turning now to the action of the secondary flux, if the left hand anode is positive and, therefore, active, the flow of current thereto produces a downward flow of secondary flux in the left hand member of the transformer core, and said secondary flux divides a portion completing its circuit through the middle member 7

and the remainder through the right hand member of the transformer core. In like manner, when the right hand anode member 2 is positive and active, the flow of current thereto produces a downward flux in the right hand member of the transformer core and said flux completes its circuit partially through the middle member 7 and partially through the left hand member of the transformer core. It will be noted that all of the secondary flux that flows through the middle member 7 flows in the same direction; that is to say, the flux is rectified and there being substantially no rate of change therein, there is substantially no resultant E. M. F. induced in the winding 8. Thus, during normal operation, there is induced in the winding 8 substantially no E. M. F. from either the primary or the secondary working flux of the transformer 6. When, however, it is desired to start the device in operation, the switches 12 and 14 are closed, imposing the unsymmetrical load 13 upon the primary winding of the transformer and causing a magnetic flux to flow in the transformer core in such manner that the two ends of the middle leg 7 are at different magnetic potentials. An alternating flux therefore traverses the leg 7, inducing an electromotive force in the winding 8, which electromotive force is imposed upon the space between the electrodes 3 and 4 through the resistance member 11 and the switch 12. By shaking the rectifier 35 1, contact is made and broken between the electrodes 3 and 4, whereupon the negative-electrode reluctance is broken down and the rectifier started into operation.

While I have shown my invention in but one concrete embodiment, it is obvious to those skilled in the art that it is susceptible of various minor changes and modifications without departing from the spirit thereof and I desire, therefore, that only such restrictions shall be placed thereupon as are specifically set forth in the appended claims or are imposed by the prior art.

I claim as my invention:

1. The combination with a vapor rectifier, of supply and load circuits therefor, a transformer connected in said supply circuit, a maintaining coil connected in said load circuit and mounted in inductive relation to the core of said supply transformer, and means for controlling the working flux of said transformer so that it may be rendered effective or ineffective in inducing a starting E. M. F. in said maintaining coil.
2. The combination with a vapor rectifier provided with main electrodes and a starting anode adjacent the main cathode, of suitable supply and load circuits connected to said main electrodes, a maintaining reactance device in said load circuit, and means 65 for inducing an E. M. F. in said reactance de-

vice tending to establish a starting arc between said starting anode and the main cathode.

3. The combination with a vapor rectifier provided with main electrodes and a starting anode, of a transformer, connections from the terminals of the secondary winding of said transformer to the main anodes of said rectifier, a connection from the cathode of said rectifier to substantially the midpoint of said secondary winding, a winding inserted in said last named connection and mounted on an auxiliary core portion of said transformer normally free from alternating flux, means for altering the magnetic conditions in said transformer whereby an alternating E. M. F. will be induced in said auxiliary winding, and connections for applying said E. M. F. to said starting anode.

4. The combination with a rectifier provided with main electrodes and a starting anode, of a transformer provided with split primary and secondary windings, connections from the outer terminals of said secondary winding to the main anodes of said rectifier, a connection from the cathode of said rectifier to substantially the midpoint of said secondary winding, an auxiliary core member on said transformer symmetrically disposed with respect to said half windings whereby it receives no magnetic flux prior to starting said rectifier, a maintaining winding in inductive relation to said auxiliary core member and inserted in said last named connection, means for altering the distribution of magnetic flux in said transformer whereby a variable flux is interlinked with said maintaining winding for the generation of an E. M. F. therein, and connections whereby said E. M. F. may be impressed between the main cathode and said starting anode.

5. The combination with a rectifier provided with main electrodes and a starting anode, of a transformer provided with split primary and secondary windings, connections from the outer terminals of said secondary winding to the main anodes of said rectifier, a connection from the cathode of said rectifier to substantially the mid point of said secondary winding, an auxiliary core member on said transformer symmetrically disposed with respect to said half windings whereby it receives no magnetic flux prior to starting said rectifier, a maintaining winding in inductive relation to said auxiliary core member and inserted in said last named connection, an auxiliary load, means for supplying said load from a portion only of the turns of said transformer, whereby the normal distribution of flux therein is altered and a variable flux caused to interlink with said auxiliary winding with the generation of an E. M. F. therein, and connections whereby said E. M. F. may be 120 125 130 135 140 145 150 155 160 165 170 175 180

impressed between the main cathode and said starting anode.

variable flux is caused to interlink with said winding and generate an E. M. F. therein.

8. The combination with a transformer, 20

of an auxiliary core member therein connecting points of equal magnetic potential when the secondary winding of said transformer is 25
thereto, and a maintaining winding inserted in the cathode lead thereof and mounted in inductive relation to an auxiliary core member of said transformer that is free from variable flux prior to the starting of said rectifier.

6. The combination with a vapor rectifier, of a transformer for supplying current 5
thereto, and a maintaining winding inserted in the cathode lead thereof and mounted in inductive relation to an auxiliary core member of said transformer that is free from variable flux prior to the starting of said rectifier.

7. The combination with a transformer, of an auxiliary core member therein connecting

points of equal magnetic potential when the secondary winding of said transformer is

15 open, a winding on said auxiliary core member, and means for altering the distribution

of flux in said transformer whereby a

variable flux is caused to interlink with said auxiliary winding with the generation 30
of an E. M. F. therein.

In testimony whereof, I have hereunto

subscribed my name this 29th day of March,

1915.

ALFRED L. ATHERTON.
